Design No. 13,522, dated January 16, 1883.

UNITED STATES PATENT OFFICE.

JOSEPHUS HARTMAN, OF PHILADELPHIA, PENNSYLVANIA.

DESIGN FOR A BISCUIT-CRACKER.

SPECIFICATION forming part of Design No. 13,522, dated January 16, 1883.

Application filed September 18, 1882. Term of patent 14 years.

To all whom it may concern:

Be it known that I, JOSEPHUS HARTMAN, a citizen of the United States, residing at Philadelphia, in the county of Philadelphia and State of Pennsylvania, have invented and produced a new and original Design for Biscuit-Crackers, of which the following is a specification, reference being had to the accompanying photographic illustration.

10 The illustration represents an oyster as a new and original design for biscuit-crackers.

I claim—

The representation of an oyster as a new and original design for biscuit-crackers, substantially as shown in the photographic illustration.

JOSEPHUS HARTMAN.
